United States Patent

Des. 240,522

Patented July 13, 1976

240,522

STATION FOR ELEVATED RAILWAY

Lawrence K. Edwards, 565 Aracadero Road,
Palo Alto, Calif. 94306

Filed Oct. 5, 1973, Ser. No. 483,925

Term of patent 14 years

Int. Cl. D25—99

U.S. Cl. D25—35

FIG. 1

FIG. 2

FIG. 3

FIG. 1 is an end elevation of a station showing my new design;

FIG. 2 is a plan view of the station; and

FIG. 3 is a side elevation of the station.

I claim:

The ornamental design for a station for elevated railway, substantially as shown.
